UNITED STATES PATENT OFFICE

CHARLES STOLL, OF ROCKAWAY BEACH, NEW YORK, ASSIGNOR TO CENTRAL FURNITURE FRAME CO. INC., OF BROOKLYN, NEW YORK, A CORPORATION OF NEW YORK

DESIGN FOR A SETTEE OR SIMILAR ARTICLE

Application filed September 24, 1929. Serial No. 32,860. Term of patent 3½ years.

To all whom it may concern:

Be it known that I, CHARLES STOLL, a citizen of the United States of America, residing at Rockaway Beach, Queens County, State of New York, have invented a new, original, and ornamental Design for a Settee or Similar Article, of which the following is a specification, reference being had to the accompanying drawing, forming part hereof, in which the single figure illustrates in perspective a settee showing my new design.

I claim:

The ornamental design for a settee or similar article, as shown.

Signed at New York city, N. Y., this 10th day of September, 1929.

CHARLES STOLL.
